RECOVERY OF HYDROCARBONS

Edward Buddrus and Samuel C. Carney, Bartlesville, Okla., assignors to Phillips Petroleum Company, a corporation of Delaware

Application July 25, 1941, Serial No. 404,080

3 Claims. (Cl. 166—21)

1

This invention relates to the production of crude oils and more particularly to a method of secondary recovery of petroleum oils from partially depleted oil reservoirs. This invention also relates to methods of preparing underground reservoirs for the storing of light volatile hydrocarbons.

Present day practice in the art of producing petroleum oils from underground reservoirs frequently employs methods of secondary recovery in order to increase the rate of fluid recovery and to drain more effectively the reservoir of its hydrocarbon fluids. Secondary recovery is usually started when a reservoir has become so depleted of its fluid that the rate of production is deemed uneconomical. Common secondary methods include such as air or gas pressure, recycling and water flooding. These fluids may be injected into, for example, one centrally located input well and the increased production withdrawn from outlying wells, or they may be injected into and increased production withdrawn from alternately located wells.

While present day methods of secondary recovery aid substantially in the recovery of petroleum fluids, there are inherent disadvantages which limit the ultimate oil recovery. For example, when fluids are injected into reservoirs at pressures substantially in excess of the existing reservoir pressure, the injected fluids may flush out the porous, permeable portions of the formations, leaving large quantities of oil in the less porous, less permeable areas. When water is injected into a reservoir precipitates and emulsions may form which plug the pores, and the use of air frequently causes plugging through tar, gum and resin formation and deposition and even paraffin deposition. And, further, present day secondary recovery methods do not remove all of the petroleum from the reservoirs.

In the practice of our invention, selected hydrocarbon vapors are injected through the well bore into the surrounding partially depleted formation at pressures of the same order as those existing in the formation. The hydrocarbon vapors selected for injection are such that at reservoir temperatures and under injection pressures they condense to liquid within the pores of said partially depleted formation. Unlike former processes, our invention does not permit channeling of the vapor even in porous and barren areas by the use of force or pressure because the vapor upon injection condenses and seals the pores with its own condensate. Condensation of these selected hydrocarbons within the pores

2

gives out latent heat and forms a solvent that is wholly miscible with the petroleum oil, lowers the surface tension and decreases the viscosity of the residual petroleum thereby assisting natural drainage into the well bore. In our preferred embodiment, we disclose the use of such hydrocarbons or hydrocarbon mixtures as propane and butane. The accumulated liquid propane and butane solvent with its charge of residual petroleum is produced from the well by pumping, separated into essentially a crude oil fraction, and a recycle fraction comprising essentially vaporous propane and butane. Our method requires only a minimum of material from outside sources, because the use of this propane and butane solvent is cyclic and the solvent supply increases as the operation progresses from the propane and butane occurring in the formation oil. And, when the secondary recovery operation is completed, the solvent used may be essentially completely recovered and the formation is then in excellent condition to serve as a storage reservoir for light petroleum products, such as butane and/or propane, which under present operating conditions are frequently not conserved due to the danger and impracticability involved in the storage of these materials in large quantities in pressure tanks.

A primary object of our invention is to provide a method of increasing recovery of petroleum oils from partially depleted oil bearing reservoirs and of storing hydrocarbons in these reservoirs during and after the recovery of the residual oil.

Another object of our invention is to provide a method of increasing the recovery of petroleum oils from partially depleted reservoirs by injecting condensable hydrocarbon vapors into the reservoir, allowing said vapors to condense to form a solvent which mixes with and reduces the viscosity and the surface tension of the hydrocarbon oil, thus facilitating drainage of the hydrocarbon fluid mixture from the formation into a well bore.

Still another object of our invention is the provision of a method of injecting into a reservoir a solvent in vapor state and recovering the solvent in a liquid state together with dissolved reservoir oil.

Another object of our invention is to provide a method of recycling hydrocarbon components of a petroleum oil, such as propane and butane, for purposes of secondary recovery of petroleum oil and conservation of the recycled components for future use.

These and additional objects and advantages will be apparent to persons skilled in the art by

reference to the following description and annexed drawing, wherein:

Figure 1 is an elevational view, partly in cross section, of one embodiment of our invention; and

Figure 2 is an elevational view, partly in cross section of another embodiment of our invention.

Referring to the drawing, and more particularly to Figure 1, we have denoted a plurality of well bores by reference numerals 10 and 11. The well bores extend downwardly from the surface of the ground 12 to a hydrocarbon bearing formation 13. Each of the well bores penetrating the formation contains a string of oil well casing 14 which is sealed at the top by a closure 15. Each closure supports a string of pump tubing 16, which conveys hydrocarbon oil from the bottom of the well bore to the surface of the ground. Reciprocating pumps 17 are provided in the lower portion of the tubing strings and are employed to lift the hydrocarbon fluid upwardly through the tubing. It is to be understood that any type of pumping equipment which can be used successfully may be employed in the practice of our invention. Pumps 17, which are shown for purposes of description, are actuated by a string of sucker rods 18 which are reciprocated by any well known pumping equipment (not shown) at the surface of the ground. An annular space 19 is formed between the interior wall of the casing and the exterior wall of the tubing of each of the aforementioned well bores. At the surface of the ground we have shown a known type of still 20 which is connected to one or more distilling columns 21 by an intercommunicating conduit 22. Still 20 also communicates with tubing 16 through a crude oil delivery line 23 and branch lines 24. Distillation of hydrocarbon liquid takes place in the still and distilling column, producing liquid fractions and a vapor fraction. The liquid fractions are drawn off from the still and the distilling column through liquid outlets 25 and 31, respectively, which convey the liquid fractions to desired disposal or storage apparatus (not shown). The vapor fraction, which consists chiefly of butane with a desired amount of propane and smaller percentages of pentane and heavier hydrocarbons, is drawn off from the distilling column by a conduit 26. It is to be understood that the components of the vapor fraction may be varied from time to time in order to facilitate the condensation of the vapor fraction which is injected into the reservoir to form a hydrocarbon solvent. This solvent reduces the surface tension and viscosity of the hydrocarbon oil in place in the reservoir, thereby facilitating drainage to the well bores. Conduit 26 is provided with branch conduits 27, which connect with closures 15 in a manner to allow communication with annular spaces 19. A by-pass 28, which communicates with a compressor 29, and a valve 30 are preferably provided in conduit 26 so that the vapors withdrawn from one well may be compressed and injected into another well along with the vapor from the distilling equipment. For descriptive purposes, we have the compressor arranged to compress vapors from well 10, and inject them into well 11, however, this is not to be considered as a limitation. Neither is our invention to be limited to any number of well bores.

In the practice of our invention, the general arrangement of apparatus illustrated in Figure 1 may be used in carrying out the steps of our method of secondary recovery and underground storage of hydrocarbon vapors. It will be noted

that hydrocarbon oil from a reservoir may contain volumes of propane and butane which are equal to as much as ten percent of the total reservoir fluid. To initiate the process, let us use well 10 as an input well for vapors coming from still 20 and distilling column 21. Additional volumes of propane and butane from an outside source (not shown) may be supplied to and vaporized in the distilling equipment as required. This butane and propane is added to the butane and propane which may be recovered from hydrocarbon oil until a desired volume of these materials is present in the formation. It may be desirable from time to time to add additional propane and butane from an outside source in order to compensate for the hydrocarbon oil withdrawn from the reservoir. The vapors evolved in the distillation process are conveyed from distilling column 21 by conduit 26, valve 30 being open, and branch conduit 27 to closure 15 of well bore 10 where the vapor is injected into the reservoir through annular space 19. During the vapor injection step it may be desirable not to pump liquid from well 10, however, well 11 may be pumped during vapor injection into well 10. It is obvious that the composition of the vapor evolved in the distilling process may be so controlled in the distilling apparatus that the vapor will contain propanes, butanes, and any heavier hydrocarbons as desired. In initiating our invention, it is frequently desirable to have a vapor consisting of small amounts of hydrocarbons which are heavier than butane.

It is a well known physical law that a vapor gives off latent heat upon condensation to a liquid. As heat always travels from a hot body to a cooler body, the heat of condensation of the vapor used in the practice of our invention will warm the formation in which condensation takes place. The large portion of the heat supplied to the formation will be the latent heat of condensation of the vapor, since only little sensible heat is available. Initially some condensation of injected vapor may occur in annular space 19, heating the casing 14 and pump tubing 16. Finally, upon continued injection, the vapors will reach the formation and become condensed therein, warming the formation locally and the contained petroleum oil. It is also known that heat lowers the resistance to flow or viscosity of a petroleum oil while the condensate of the injected vapor is also less viscous and has a lower surface tension than the formation oil.

The condensed vapor acts as a solvent and mixes with the formation oil increasing the temperature thereof and of the formation. A portion of the injected vapor will be dissolved by the formation oil resulting also in a rise in temperature. This temperature increase combined with the solvent action of the condensed and dissolved vapors lowers the surface tension and decreases the viscosity of the oil materially thereby facilitating drainage of the oil-solvent mixture to the well bore. It will be seen that the above step in our process takes place in a small area initially, and spreads out over a greater portion of the formation as the temperature of the formation increases and the oil in the reservoir and condensed vapors are drained to the input well bore and produced therefrom.

By the condensation of the injected vapors, the latent heat of condensation will sufficiently warm the formation in which condensation takes place so that continued condensation of the injected vapors will not occur in this immediate area.

This warming then allows the process to remove the formation oil from progressively further from the point of initial vapor injection. As the upper portion of the formation is usually the more completely drained, the injected vapors will condense in the upper portion first. Thus, the condensed vapors readily drain to the lower portions of the formation to mix with the hydrocarbon oil therein, assisting the drainage of the residual oil to the well bore. The mixture of oil and propane-butane solvent which accumulates in well bore 10 is periodically removed by pump 17 to the surface through tubing 16, and is then passed to still 20 by way of branch line 24 and line 23. The oil solvent mixture is distilled in still 20 and distilling column 21 in which the liquid fractions are drawn off through conduits 25 and 31, respectively and the vapor fraction through line 26, valve 30 and line 27 is recycled in the heretofore mentioned manner. It is to be noted that as the petroleum oil is removed from formation 13 and distilled and the propane and butane therefrom recycled, the proportion of these hydrocarbons in the cycle and therefore in the reservoir, increases particularly in the immediate area of injection where the increase is very great. The injection of vapor may be continued until essentially all of the residual oil has been removed from the formation immediately surrounding well 10, and the condensation of vapors spreads over the formation to facilitate the drainage of the residual oil to well bore 11 as well as to well bore 10 or other well bores (not shown), from which the condensed vapor and oil solution may be recovered as a liquid. At such time as deemed expedient, the injection of vapors may be directed to another well or wells such as to well bore 11 in the manner similar to that disclosed in relation to well 10. When essentially all the oil has been removed from the formation by the recycling of the propane-butane vapors, the pores of the formation will be filled with the propane-butane in any desired propane-butane volumetric ratio.

At this time the reservoir is prepared for and may be utilized for storage of the vapors already present in the formation. By increasing the injection pressure of the vapor, additional volumes of butane or propane may be injected into and stored in the formation. As the vapor stored in the reservoir will be at superatmospheric pressure, it may be recovered from the formation with the aid of its own vapor pressure. When the pressure of the vapors in the reservoir is reduced to atmospheric, the remaining vapors may be recovered by applying a partial vacuum to the formation.

It will be noted that while we have described our method specifically with respect to one input well, any number of input wells may be used for injection of the vapors as predicated by the operating conditions which may be peculiar to a given petroleum containing formation. Further, the injection of the vapors through annular space 19 is optional, since this may be carried out advantageously through tubing 16 by the inclusion of a by-pass (not shown) between tubing 16 and branch conduit 27 and by unseating pump 17 during periods of vapor injection.

Another modification of our invention may be practiced advantageously at a time when the injection of vapor from the surface distilling equipment has removed the oil for a considerable distance back in the formation surrounding the input well bore, but prior to the time that the

injected vapor facilitates drainage to an offset producing well. At such time, as deemed expedient, vapor injection to well bore 10 may be discontinued. With no vapor being injected or withdrawn from well bore 10, the temperature and pressure of the vapor in the formation surrounding the well bore, which has been drained of hydrocarbon oil, reaches equilibrium. Vapor may then be removed from well bore 10 and delivered to well bore 11, along with additional vapor from the surface distilling equipment. This is accomplished by closing valve 30 in conduit 26 and directing the vapor through compressor 29, which increases the pressure of the vapor coming from well bore 10 to that of the vapor coming from the surface distilling equipment. By removing vapor from well bore 10, the surrounding formation is virtually converted into a still. The liquid there is at its equilibrium boiling point at the former operating pressure. It is, therefore, in the condition of live oil originally contained in the sand and will give off vapor freely to replace itself and so will drain freely, being driven out of the pores by its own vapor. After utilizing some of the stored heat by evaporation, governed by the rate of pressure reduction, vapor injection may be renewed while vapor is removed from another input well. It is to be noted that by injecting vapor from one of the wells, part of the latent heat of condensation is used advantageously. The alternate injection of vapor from first one well to another and then reversing the step, may be carried out until essentially all of the hydrocarbon oil has been removed from the formation and the formation thus properly conditioned for the storage of hydrocarbon vapors already present in the formation and for such additional vapors as may be injected into the formation for storage.

Referring to Figure 2 for a description of another modification of our invention, it will be noted that the apparatus is identical to that of the first modification, except that a packer 31 is carried on the tubing string and set in the uncased portion of the well bore below the top of the formation and above pump 17 in such a manner that only the upper portion of the formation communicates with annular space 19. In this modification, the injection of vapors through the annular space is carried on continuously without shutting down the pumping operation of the well. As the vapors condense and dissolve in the hydrocarbon oil in the upper part of the formation, the liquid drains to the lower portion of the formation and thence into the well bore, carrying with it oil in greater quantities than would otherwise drain thereto, because the liquid has reduced the viscosity and surface tension of the oil as heretofore disclosed. The method of this modification of our invention is otherwise identical with the first. It is to be noted that the vapor above the packers may be withdrawn from well bore 10, if desired, and injected into well bore 11 in the manner heretofore described.

It is emphasized that this is not essentially a pressure process. On the contrary, it is desirable that pressures in the sand be held reasonably low so that the pores which have been emptied of liquid may be filled with a minimum of vapor. It is a process in which the vapor pressure of the oil in place is built up to a higher value by the cyclic returning of volatile material, largely derived from the oil being produced, while

at the same time temperature is raised in the zone of condensation.

Though we have described 10 as an input well and 11 as a pumping well, it is desirable to use all wells, at the start, as input wells. The purpose of this is to clean out the sand body near them and to raise the temperature, locally, so that in effect the diameter of the hole in the sand is increased by providing a larger cross section of open sand through which drainage can occur.

As will be obvious, the process results in the production first of the heavier hydrocarbons of the crude oil. It, therefore, affords a means, to a refinery located near old producing sands of this type, for producing the heavier oils without the consequent increase in gasoline stocks and likewise a means of storing gasoline and lighter fractions under ground while using such storage as a recovery means.

The underground temperature at the condensing point may be computed from knowledge of the pressure, together with analysis of the vapor being injected and liquid phase being pumped. It is desirable to change the composition of vapor being returned as more of the sand is exhausted by the process, by the inclusion of more propane and even methane so that the exhausted pores may be filled with vapor of high volatility. Then when recovery of oil is considered economically complete, the composition of vapor returned should have been so controlled that injected material then present in the sand should consist of substantially nothing heavier than butane and that chiefly present as vapor. The final termination of a project consists of pumping down the liquid level to the lowest point geologically and then exhausting the vapor by vacuum pumps and using the stored heat to evaporate liquid which wets the lower part of the sand.

The process is best adapted to lenticular structures of high porosity and high permeability in which there is no water drive. In addition to recovering crude petroleum oil which otherwise might be lost, a special utility of our invention lies in the storage or deferred production of lighter hydrocarbons. Its use is well adapted to reduce the overproduction of motor fuel in winter when market demand for furnace oil is heavy and to permit building up of stocks of butane and propane underground pending development of a synthetic rubber industry, the cost of storage of these aboveground being prohibitive because of their vapor pressure.

From the foregoing, it is believed that the many advantages obtainable by the practice of the present invention will be readily apparent to persons skilled in the art. However, since many changes may be made in carrying out the above method without departing from the scope of the invention, as defined by the appended claims, it is intended that all matter contained herein shall be interpreted as illustrative and explanatory, rather than in a limiting sense.

We claim:

1. A method of preparing partially depleted oil bearing formations for volatile hydrocarbon

storage including the steps of injecting condensable hydrocarbon vapor consisting of propane and butane at substantially atmospheric temperature and at a maximum pressure only slightly higher than the vapor pressure of propane at formation temperature into the partially depleted oil bearing formation through an input well, permitting the injected vapor to condense substantially completely to a liquid within the pores of the formation thereby warming and dissolving the oil to facilitate drainage of the oil into the input well bore and into adjacent well bores, producing the mixture of oil and fully condensed vapor from the input and adjacent well bores, fractionating this mixture into a crude oil bottoms and the condensable hydrocarbon vapor, recycling the vapor and producing the condensed vapor and oil mixture until a suitably large storage reservoir has been essentially freed of its crude oil content.

2. A method of preparing partially depleted oil bearing formations for volatile hydrocarbon storage including the steps of injecting condensable hydrocarbon vapor consisting of propane and butane at substantially atmospheric temperature and at a maximum pressure only slightly higher than the vapor pressure of propane at formation temperature into the partially depleted oil bearing formation through an input well, permitting the injected vapor to condense substantially completely to a liquid within the pores of the formation thereby warming and dissolving the oil, reducing the pressure and permitting at least some of the dissolved solvent to vaporize to replace the oil-solvent solution by solvent vapor to facilitate drainage of the oil into the input well bore and into adjacent well bores, producing the mixture of oil and condensed vapor from the input and adjacent well bores, fractionating this mixture into a crude oil bottoms and the condensable hydrocarbon vapor, recycling the vapor and producing the condensed vapor and oil mixture until a suitably large storage reservoir has been essentially freed of its crude oil content.

3. A method of producing petroleum oil from partially depleted wells including the steps of injecting condensable hydrocarbon vapors consisting essentially of propane and butane at substantially atmospheric temperature and at a maximum pressure only slightly higher than the vapor pressure of propane at formation temperature into the partially depleted oil producing formation, permitting the injected vapors to condense substantially completely within the pores of the formation thereby warming by the available heat of condensation the residual crude oil and dissolving said residual oil, producing this mixture of fully condensed propane and butane and petroleum oil, fractionating this mixture into a crude oil bottoms and a propane and butane vapor, and recycling the propane and butane vapor into the partially depleted oil producing formation.

EDWARD BUDDRUS.
